(57) **CLAIM**

The ornamental design for an enclosure with security and weatherproofing, as shown and described.

DESCRIPTION

FIG. 1 is a perspective view of an embodiment of an enclosure with security and weatherproofing in the open position;

FIG. 2 is a rear-perspective view of the enclosure with security and weatherproofing of FIG. 1;

FIG. 3 is an exploded perspective view of the enclosure with security and weatherproofing of FIG. 1;

FIG. 4 is a perspective view of the enclosure with security and weatherproofing of FIG. 1 in a closed position;

FIG. 5 is a rear-perspective view of the enclosure with security and weatherproofing of FIG. 1 in a closed position;

FIG. 6 is a top view of the enclosure with security and weatherproofing of FIG. 1;

FIG. 7 is a bottom view of the enclosure with security and weatherproofing of FIG. 1;

FIG. 8 is a left side view of the enclosure with security and weatherproofing of FIG. 1;

FIG. 9 is a right side view of the enclosure with security and weatherproofing of FIG. 1;

FIG. 10 is a front view of the enclosure with security and weatherproofing of FIG. 1;

FIG. 11 is a rear view of the enclosure with security and weatherproofing of FIG. 1;

FIG. 12 is a top view of the enclosure with security and weatherproofing of FIG. 1 in a closed position;

FIG. 13 is a front view of the enclosure with security and weatherproofing of FIG. 1 in a closed position;

FIG. 14 is a rear view of the enclosure with security and weatherproofing of FIG. 1 in a closed position;

FIG. 15 is a right side view of the enclosure with security and weatherproofing of FIG. 1 in a closed position; and,

FIG. 16 is a left side view of the enclosure with security and weatherproofing of FIG. 1 in a closed position.

The broken lines represent portions of the structure or environment that form no part of the claim.
